Act 3

UNITED STATES PATENT OFFICE.

FRANK A. RANDALL, OF CHICAGO, ILLINOIS.

CONCRETE-FORM.

1,293,921.

Specification of Letters Patent. Patented Feb. 11, 1919.

Application filed October 3, 1916. Serial No. 123,492.

To all whom it may concern:

Be it known that I, FRANK A. RANDALL, a citizen of the United States, residing at Chicago, in the county of Cook and State 5 of Illinois, have invented a certain new and useful Improvement in Concrete-Forms, of which the following is a full, clear, concise, and exact description.

My invention relates to improvements in 10 concrete forms.

The object of the invention is to provide a form which may be removed from the concrete after the latter has hardened, much more quickly and conveniently than those 15 used heretofore.

In the accompanying drawing, I have illustrated a construction which embodies the invention.

Figure 1 is a top plan view of a concrete 20 floor partly broken away to show the form beneath.

Fig. 2 is a section on the line 2—2 of Fig. 1.

Fig. 3 is a top plan view of a modified 25 construction, and Fig. 4 is a longitudinal section taken through one end of one of the horizontal boards of the form.

The form is built up in the case of the 30 flooring illustrated, by means of temporarily supported planks 1, 1, which support the inclined boards 2—2 thereon. The top members consist of horizontal boards 3—3. They are supported on transverse toggle members consisting of boards 4—5 secured at their 35 ends by boards 6—6 and 7—7. The boards 5 rest on the margins of the planks 1 and the boards 3 rest on the boards 4. The side boards 2—2 rest against the ends of the toggle members. The boards 7—7 project 40 downwardly beneath the toggle members and are held in the desired relation by suitable fastening means such as iron loops 8 and wedges 9. After the concrete 10 has been poured and hardened the form may be read- 45 ily removed by first driving out the wedges 9, taking off the loops 8, moving the toggle members to the position shown in Fig. 1 and removing them.

It will be noted that the meeting edges of 50 the boards 4—5 are beveled at 11 thereby permitting relative angular movement of the toggle members. Furthermore the boards 6 are secured to the opposite sides of the boards 4—5 from those to which the boards 55 7 are secured. Therefore, the line of pressure produced by the concrete when it sets,

is directed about midway between the double thickness produced by the boards at the outer ends of the toggle members. In other words, the line of pressure is indicated approximately by 12. Said pressure, therefore, tends to break the toggle joint as soon as the latter is freed of the restraining loops 8 and wedges 9.

To facilitate removal of the horizontal 65 boards 3, the ends of the latter are connected by battens 13, adjacent to which, sheet metal angle plates 14 are located. Said angle plates have openings 15 therein into which a bar may be inserted to pry the boards 3 away 70 from the concrete after the toggle members and side boards 2, 2 have been removed. The side boards are also preferably fastened together by battens 16. All of said boards are therefore readily removed. The planks 75 1, 1 are supported in some suitable manner during the construction of the form and during the pouring operation.

The form illustrated in Fig. 3 is the same as shown in Fig. 1 except that the toggle 80 members are hinged to the side boards by hinges 17. They are also hinged to each other by additional hinges 18. With this arrangement, the side boards and the toggle members are removed together.

Great difficulty has been experienced heretofore in removing forms of this character from the concrete without damaging said forms. The tamping of the concrete and the swelling of the timbers, due to the absorption of moisture, causes the parts to bind, thereby rendering the removal of the forms a difficult operation. With the present arrangement, this binding pressure is resisted by the toggle members and is so 90 utilized as to make it easier to remove said members rather than to make it more difficult. The forms are preserved intact and may be used repeatedly in subsequent building operations.

For convenience in disclosing the invention, I have illustrated it as applied to a floor construction in which some members have been referred to as horizontal and others as vertical. It is to be understood 105 however, that these terms have been used merely in a relative sense. The invention is applicable to concrete forms arranged vertically as well as horizontally or at any angle. Furthermore, I do not wish to limit myself 110 to wooden forms, as it is obvious that the required forms made of metal, or any other

suitable material may be employed. In general the invention is not to be limited to the details of construction or relative arrangement of parts described herein except where limitations appear in the appended claims.

Having thus described my invention, what I claim as new and desire to secure by Letters Patent of the United States is:

- 10 1. A concrete form comprising side members and top members, pivoted members arranged to hold said side members apart and to support said top members and means for holding said pivoted members in alinement but permitting them to be moved angularly and removed.
- 15 2. A concrete form comprising bottom members, pivoted members resting thereon, top members resting on said pivoted members and upright members against the ends of the pivoted members, said pivoted members being beveled at their meeting edges whereby the pressure developed during the setting of the concrete tends to break the 25 pivoted joint and means for preventing such movement.
- 30 3. In a concrete form, a toggle member consisting of compression members having their meeting edges beveled, reinforcing members at right angles to said compression members and adjacent to said beveled edges, said reinforcing members projecting beyond said compression members, metal loops surrounding said projecting portions and 35 wedges for tightening said loops.
- 40 4. A concrete form comprising side members and top members, a toggle joint for holding said side members apart and for supporting said top members and means projecting from said top members between said toggle joints, affording means for forcibly removing said top members.

5. A concrete form comprising horizontal boards spaced apart, inclined boards supported thereon back from the edge thereof, 45 toggle members supported at intervals on the margins of said boards, horizontal boards supported on said toggle members even with the tops of said inclined boards, battens connecting the ends of said top 50 boards, sheet metal angles having openings therein secured to the under side of said top boards to facilitate removal thereof and means for holding said toggle members in the same plane until after the concrete has 55 set.

6. A concrete form comprising side members, compression members pivoted together and arranged in alinement between said side members to hold the latter apart, abutments 60 on said compression members adapted to prevent movement thereof out of alinement in one direction but permitting such movement in the opposite direction, and means for locking said compression members in 65 alinement, the binding of said side members against said compression members acting to automatically release the latter upon the removal of said locking means.

7. A form for plastic material comprising side members, pivoted members adapted when in alinement to hold said side members apart, and temporary locking means for positively maintaining said pivoted members in operative position, the lateral 75 pressure created by the pouring of plastic material into said form acting to automatically displace said pivoted members upon the removal of said locking means.

In witness whereof, I hereunto subscribe 80 my name this 30th day of September, A. D. 1916.

FRANK A. RANDALL.
